UNITED STATES PATENT OFFICE

EDWARD R. VAN BERGEN, OF CLEVELAND HEIGHTS, OHIO

STENCILING APPARATUS

Application filed November 21, 1928. Serial No. 320,937.

The present application relates, as indicated, to stenciling apparatus, and more particularly to devices for facilitating the production of color sheets of the type disclosed in my copending application for display device, Serial No. 285,045, filed June 13, 1928. The primary object of the invention is to provide means for accelerating the production of a plurality of duplicate designs upon a like number of separate elements. Further objects will appear as the description proceeds. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a perspective view of one form of apparatus constructed in accordance with my invention; Fig. 2 is a bottom plan view of a fragment of the stencil sheet; Fig. 3 is a plan view of a color sheet produced through the use of the apparatus disclosed in Fig. 1; Fig. 4 is a perspective view of a modified form of apparatus; Fig. 5 is a perspective view of a third embodiment of the present invention; Fig. 6 is a plan view of one of the frames illustrated in Fig. 5; Fig. 7 is a section taken substantially upon the line 7-7 of Fig. 6; and Fig. 8 is a plan view of a modified element of the organization disclosed in Fig. 5.

Referring more particularly to the Fig. 1, it will be seen that the apparatus therein disclosed comprises a platform 10 adjacent which there is mounted a shaft 11 so journaled that said shaft makes an acute angle with the horizontal, said shaft mounting a large drum 12. On one side of said drum, there is mounted a spindle 13, and on the opposite side of the drum there is mounted a second spindle 14. As is clearly shown, the forward ends of said spindles 13 and 14 are journaled in brackets 15, while the opposite

ends thereof are journaled in elevated brackets 16, whereby the axes of the spindles 13 and 14 are made parallel with the axis of the shaft 11. The spindle 14 is provided with a crank arm 17, and the spindle 13 is provided with brake means (not shown).

Extending over the periphery of the drum 12 and having its ends wound upon the spindles 13 and 14 there is a sheet 18 of suitable flexible material formed with a plurality of stencil apertures 19 which are preferably arranged, as shown, in banks. Each of said stencil apertures is surrounded by a plurality of diagonal slots 20 for the accommodation of the corners of sheets 21 upon which a design is to be stenciled.

In operation, an operator stands upon the platform 11 with a spray gun 22. A second operator stands to the left of the first adjacent the spindle 13 and, as the sheet 18 is unrolled from said spindle 13, this latter operator inserts the corners of a sheet 21 in the slots 20 adjacent each stencil aperture 19. The sheets 21 are thus held smoothly in contact with the lower surface of the sheet 18. The sheet is moved forwardly (i. e., toward the spindle 14) by operation of the crank 17 or by a motor, the sheet being moved quite slowly and under tension applied by the brake means of the spindle 13. As the sheet moves forward over the drum 12, it is held by such tension smoothly against said drum and the drum rotates upon its shaft 11. As each bank of stencil apertures passes the operator on the platform 10, he thoroughly sprays the exposed portions of each sheet 21 through its respective stencil aperture, thus producing the design 23. The lacquer used in the gun 22 is of a quick drying type, and the movement of the sheet 18 is necessarily quite slow so that, before the stenciled sheets 21 reach the spindle 14, they are sufficiently dry to be removed from the sheet.

In Fig. 4 I have shown a section of a drum 24 upon which is mounted a stencil 25 having a stencil aperture 26. To the lower surface of said stencil 25 there is secured a sheet 27, the corners of said sheet being extended through slots 28 formed in the stencil 25.

Any suitable means such as the resilient strap indicated at 29 in Fig. 4 may be used for holding the stencil and its attached sheet smoothly on the drum. Obviously, a plurality of such stencils may be secured to a drum, sprayed, and removed therefrom to provide for a continuous process.

In Figs. 5 to 8 inclusive, there is disclosed a third type of apparatus embodying my invention. According to this embodiment, a booth 30 having side walls 31 and 32 provided, said side walls being formed with parallel slots 33. On the wall 31 there is mounted a cylinder 34 from which there extends an air hose 35 for operating a spray gun 36. A board 37 is slidably mounted in the slots 33, and on said board there are mounted a plurality of frames 38. As is clearly shown in Fig. 6, each of said frames 38 has secured thereto a pair of hinges 39 through the medium of which said frame is mounted on the support. On the edge of each frame opposite that edge to which the hinges are secured there is provided a handle 40, and around the border of the frame, there are provided a plurality of clips 41 for securing in said frame a stencil 42 provided with any suitable form of stencil aperture 43. In practice, of course, the board 37 can be any desired length, though the length indicated is preferable. While the board 37 is in the position indicated in Fig. 5, the operator is spraying lacquer upon the sheet 44 held between the board 37 and frame 38a. A corresponding sheet 44 beneath the frame 38 has been sprayed and is drying, and a blank sheet has been inserted beneath the frame 38b. When the spraying of the sheet in the frame 38a has been completed, the board 37 is slid toward the right, thus bringing the frame 38b into position to be sprayed. While the sheet in the frame 38b is being sprayed, the finished sheets in the frames 38a and 38 are removed and blank sheets are placed therein. Then, after the spraying of the sheet in the frame 38b is completed, the board is moved to the left to bring the frame 38a, and later the frame 38 into position to be sprayed.

In Fig. 8 I have shown a slight modification of the above arrangement in which the board 37' is substantially wider than the board 37 to permit the mounting of double banks of frames 38' thereon.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a device of the class described, an element formed with a plurality of stencil

apertures, means for moving said element past an operator, and means for securing to the side of said element remote from the operator, a piece of material to be treated.

2. In a device of the class described, an element formed with a plurality of stencil apertures, means for moving said element past an operator, and means for securing to the side of said element remote from the operator, a piece of material adjacent each of said apertures. 70

3. In a device of the class described, an element formed with a plurality of stencil apertures, means for moving said element past an operator, said element being formed to provide means for securing to the side thereof remote from the operator, a sheet in registry with each of said apertures. 80

4. In a device of the class described, an element formed with a plurality of banks of stencil apertures, means for moving said element past an operator, and means for securing to the side of said element remote from the operator, a piece of material to be treated. 85

5. In a device of the class described, a drum, a pair of spindles mounted on opposite sides of said drum, and a flexible sheet formed with a plurality of stencil apertures and having its ends wound on said spindles, respectively, said sheet being adapted to overlie the surface of said drum. 90

6. In a device of the class described, a drum, a pair of spindles mounted on opposite sides of said drum in paraxial relation thereto, and a flexible sheet formed with a plurality of stencil apertures and having its ends wound on said spindles, respectively, said sheet being adapted to overlie the surface of said drum. 100

7. In a device of the class described, a drum, a pair of spindles mounted on opposite sides of said drum, and a flexible sheet formed with a plurality of stencil apertures and having its ends wound on said spindles, respectively, said sheet being adapted to be tensioned on the surface of said drum by said spindles. 105

8. In a device of the class described, a platform, a drum mounted upon an axis making an acute angle with the horizontal, a pair of spindles mounted on opposite sides of said drum in paraxial relation thereto, and a flexible stencil sheet overlying said drum and having its ends wound on said respective spindles. 115

9. In a device of the class described, a platform, a drum mounted upon an axis making an acute angle with the horizontal, a pair of spindles mounted on opposite sides of said drum in paraxial relation thereto, and a flexible stencil sheet overlying said drum and having its ends wound on said respective spindles, said sheet being formed with a plurality of slots adjacent each of its stencil apertures. 125

10. In a device of the class described, elongated means mounting a plurality of stencils, and means for moving said first-mentioned means past an operator.

5 Signed by me this 19th day of November,
1928.

EDWARD R. VAN BERGEN.
